UNITED STATES PATENT OFFICE.

WALTER S. ADAMS, OF PHILADELPHIA, PENNSYLVANIA, ASSIGNOR TO THE J. G. BRILL CO., OF PHILADELPHIA, PENNSYLVANIA, A CORPORATION OF PENNSYLVANIA.

SWEeper FOR RAILROAD-TRACKS.

1,161,574.

Specification of Letters Patent. Patented Nov. 23, 1915.

Application filed August 26, 1913. Serial No. 786,661.

To all whom it may concern:

Be it known that I, WALTER S. ADAMS, a citizen of the United States, and a resident of the city and county of Philadelphia, State of Pennsylvania, have made a new and useful Improvement in Sweepers for Railroad-Tracks, of which the following is a specification.

The object of my invention is to provide a suitable device which will positively drive the broom so as to properly sweep the space adjacent to and over the tracks at any desired level and to provide a suitable mechanism for raising and lowering the brooms as the exigencies of sweeping may require. This object is accomplished by my invention, one embodiment of which is herein-after set forth.

For a more particular description of my invention, reference is to be had to the accompanying drawings, forming a part hereof, in which:

Figure 1 is a plan view with parts removed, of a portion of my improved sweeper; Fig. 2 is a sectional view taken on the line 2—2 of Fig. 1, looking in the direction of the arrows; Fig. 3 is an end view of a brush and a portion of the supporting mechanism; Fig. 4 is a sectional view taken on the line 4—4 of Fig. 1, looking in the direction of the arrows; Fig. 5 is a plan view of a portion of the frame, a part of the floor of my improved sweeper and a part of the mechanism being shown; Figs. 6 and 7 show the sweeper supporting mechanism and parts connected therewith, Fig. 7 being taken at right angle to the structure shown in Fig. 6; and Fig. 8 is a sectional view taken on the line 8—8 of Fig. 1.

Throughout the various views of the drawings, similar reference characters designate similar parts.

A sweeper provided with my improvement is provided with any suitable running gear, not shown, which carries a frame 1 of the conventional kind. This frame 1 has longitudinal sills 2 and 3, an end sill 4 and suitable crossings 5 together with short longitudinal bars 7 and 8 which are placed so as to support parts of the mechanism described below.

The frame 1 carries a suitable floor 9 with parts raised above the motor and superstructure 10, which may be of any desired form.

Two of the crossings 5 are connected by

suitable longitudinal bars 11 and 12, and the lower edges of these bars are connected by suitable cross bars 13 and 14, which support bearings 15 and 16 in which is journaled the main shaft 17 of the machine, so that this shaft is carried in the frame 1 of the machine. This shaft 17 is connected by suitable clutches 18 and 19 with the secondary shafts 20 and 21 respectively. These shafts 20 and 21 are in alinement with the shaft 17 and are mounted in suitable bearings 22 carried by and against the crossings 5.

The clutch 18 is actuated by the handle 23 which is connected by any suitable means to the movable member of this clutch, and in the same manner the clutch 19 is actuated by the handle 24. By shifting the respective handles, the shafts 20 and 21 may be connected or disconnected from the shaft 17, as desired. The shaft 17 is driven by a suitable motor 25 mounted on this shaft in the same manner as the street railroad motor is ordinarily mounted on the axle of a truck. One end of this motor 25 is supported by the shaft 17 on which it is sleeved and the other end is spring supported at 26 by means of a suitable bar 27 which runs from the motor, and to which it is secured. This motor is connected in the usual manner to a suitable controller and other instruments, so that it may be rotated and be controlled by the motorman or other person operating the sweeper.

As the shafts 20 and 21 are connected in the same way to their respective brushes or sweepers, a description of one connection will answer for both. Each of these shafts is provided with a suitable bevel gear 28 which is fixed thereon and rotates therewith. This bevel gear 28 meshes with a corresponding gear 29 slidably mounted on a suitable shaft 30 in such a way that this gear 29 will always rotate about the axis of this shaft and drive the same. This shaft 100 may be given any suitable shape consistent with its functions, as non-circular in cross section, or circular with a key and slot connection. The gear 29 has a suitable bushing 31 mounted thereon, which bushing revolves in a suitable bracket 32, so that this bracket 105 performs the double purpose of being a support and bearing both for the gear 29 and the shaft 30. The bracket 32 is secured to the bars 7 and 8 in any suitable manner. 110

The lower end of the shaft 30 is provided with a suitable gear 33 mounted in a bushing 34 which revolves a suitable bearing 35 which bearing is supported from a hanger 36 which is secured to the frame 1 of the machine and preferably to the bracket 32 or in any other suitable manner. The bearing 35 slides freely in a vertical direction upon the bracket 36 and also serves as a bearing for 10 a horizontally disposed sweeper shaft 37 on which the sweeper brushes 38 are mounted. As these brushes are of the conventional form and have conventional mounting, it is not necessary to describe them in detail. It 15 is sufficient to say that there are two of them and that they are fixed on the shaft 37 so as to revolve with the same and that this shaft 37 is driven by means of a suitable bevel gear 39 which meshes with the gear 33. 20 Each of the ends of the shafts 37 is suitably journaled in a bearing 40 which has a vertical movement on suitable brackets or guides 41 or 42. These brackets are secured to the frame 1 of the machine in any 25 desired manner. Each of them has a vertical bar corresponding to the vertical bar of the bracket 36 and parallel therewith, so that the bearings 40 and the bearing 35 will always move parallel to each other. The 30 means for raising and lowering the bearings 40 and the shaft connected thereto will now be described.

Each of the bearings 40 has an upwardly extending pair of ears 43 which are provided 35 with a suitable pin, and the pin of each bearing engages the lower end of a suitable link 44 which at its upper ends articulates with a lever 45 in the usual manner. Each lever 45 near the bracket 41 runs to a suitable shaft 46 journaled in suitable bearings 47, which are secured on the upper side of the frame 1 of the car.

Near the bracket 42 is a third lever 48, the free end of which is bifurcated and provided with a bearing 49 to receive lugs 50 and a nut 51 mounted on a vertical screw shaft 52 which is journaled in suitable brackets 53 and 54, both of which are secured to the frame 1 and the floor 9, and the 55 upper end of the shaft 52 is provided with a suitable hand wheel 55 or any other suitable means by which the shaft 52 may be turned in either direction. By turning this shaft in one direction the lever 49 is lowered and by turning it in the other direction, the

lever is elevated, by the weight of the shaft 37 and the parts carried thereby or mounted thereon, so that by turning this wheel 55 in one way or the other, the brushes may be raised or lowered, as the exigencies of sweeping may require.

In view of the foregoing, the operation of my improved sweeper will be readily understood. The brushes are caused to rotate, preferably one pair at a time, and preferably the pair at the front of the machine, by articulating one or the other through the clutches 18 or 19, to the shaft 17. Both of the brushes are capable of being raised or lowered idle or running, it makes no difference which, they may be raised or lowered, by turning the wheel 55 as above described, whereby they may be kept at any desired position for the purpose of sweeping the tracks, or cleaning the tracks when out of use. It will be noted that whether raised or lowered, they are raised or lowered in a vertical plane and that they are positively driven by gears at all times, in any position, when the clutches are thrown to produce 80 this result.

While I have shown and described but one embodiment of my invention, it is obvious that it is not restricted thereto, but is broad enough to cover all structures that come 85 within the scope of the annexed claim.

Having thus described my invention, what I claim is:

In a machine of the class described, a frame, a shaft journaled in said frame with 90 its axis lying longitudinally of the car, said shaft being divided into three parts, the center being connected with the motor, clutches connecting the center part with the other parts, a motor attached to said center 95 part, brushes and means for mounting the same from said frame so that the brushes may be raised or lowered in vertical planes, and gears and a vertical shaft connecting one brush with each end shaft, so that when 100 the device is in use, either brush may be driven by said motor at any place of its elevation.

Signed at the city of Philadelphia, county of Philadelphia, and State of Pennsylvania, 105 this 15th day of August, 1913.

WALTER S. ADAMS.
